DRY CARGO SHIPS

Robert Knut Oskar Fredrikson, 35 Stigbergsgatan,
Stockholm, Sweden

Filed Feb. 24, 1958, Ser. No. 717,151

Claims priority, application Sweden Feb. 26, 1957
6 Claims. (Cl. 114—72)

The object of the present invention is to construct a dry cargo ship in such a way that the strain on the hull in its longitudinal direction is reduced by such a construction of the ship's hull that heavy loads can always be placed amidships and lighter loads wherever desired, while the accessibility of the different loads is better than in dry cargo ships of conventional design.

Normally dry cargo ships have a hull which in its longitudinal direction is provided with a plurality of transverse bulkheads and in vertical direction with one or more decks. The cargo-holds and 'tween-decks between the transverse bulkheads, decks and the tank top or inner bottom plating are loaded and unloaded through cargo-hatches arranged on the centre-line of the ship.

As a rule, the decks are supported either by means of longitudinal bulkheads arranged in the centre line or by vertical pillars in one or more rows stretching from the tank top via the different decks up to the weather deck. The construction of the ship's double bottom, containing the so-called internal bottom (floors, centre line and intercostal longitudinals, margin plates and tank top) is so stiff that by its nature it serves as a foundation for said pillars and/or centre-line bulkheads. If a deck were to be arranged without supports from the internal bottom or tank top it would be necessary considerably to strengthen the deck beams and their joints to the side frames. Thus it would be necessary to use a plurality of bulky deck beams in the cargo-space attached to very deep frames, all resulting in a considerable decrease of the useful space of the cargo-hold and 'tween-decks and increase of the weight of steel, in consequence whereof the load capacity of the ship is decreased.

The requirement of adequate longitudinal strength of the ship has developed a construction wherein that one deck, the strength deck, is given such a thickness that the hull, considered as a beam, will be sufficiently strong. For ships with slim hulls and high speed, the requirement for longitudinal strength is accentuated. Such ships must often fulfill the requirement of being able to transport cargos with very different weights per cubic foot of load, as for instance so called refrigerated space load, which as a rule is a light load, and case-goods and/or bulk goods (corn, ore), which are heavy loads. Obviously it is not of advantage to have refrigerated rooms, i.e. rooms provided for light loads, concentrated amidships where the displacement (upward forces) is largest and the load smallest, while heavier loads are placed towards the ends of the ship, where the displacement is smallest. The experiences of the past unequivocally show that such arrangements are not advantageous and this due to the fact that the hull is exposed to large stresses and that the possibility of permanent damage to the ship hull increases. The desire to be able to place heavy load where the displacement of the ship is large can, however, be fulfilled provided that it is possible to place this heavy load on the tank top of the double bottom of the hull, which is best suited to carry heavy load. This in its turn is conditional among other things upon the tank top not being provided with insulation for refrigerated cargo, and, consequently, that refrigerated spaces are not arranged on the tank top. It is thus necessary to provide for lighter loads, for instance refrigerated space loads, at other parts of the hull than on the tank top. Hitherto this space has been provided for by "trunking-in" certain 'tween-deck

2

hatches, the vertical walls of the trunks being provided with trunk ports for loading and unloading. The cargo has been loaded through said trunked-in cargo-hatches at the centre-line of the ship and then been carried or 5 dragged in a horizontal direction through the trunk ports and placed in the 'tween-deck space. It has thus been necessary to load the 'tween deck cargo-spaces of the hatch last and to unload it first in order to be able to obtain access to the lighter loads (refrigerated space loads).

The present invention relates to such a disposition of the cargo-spaces that, with due consideration to the consumption of a minimum of steel for providing sufficient longitudinal strength of the ship, the ship shall be adapted 10 for carrying light loads (refrigerated space loads) as well as heavy loads (corn, ore, case-goods), while the loading and unloading of such different cargos independently of each other shall be possible. The cargo is stowed in cargo-holds and 'tween-decks which, as far as possible, 15 are entirely free from vertical supports, thus facilitating the handling of the loads.

According to the present invention this purpose is attained by subdividing the transverse section of the hull in the vertical direction between the strength deck of the 20 ship and the internal bottom plating (tank top) by at least one lower deck stretching from one side of the hull to the other, without supporting said deck between the transverse bulkheads of the cargo-hold by any kind of vertical supports, centre-line bulkheads or brackets along the side 25 plating with accompanying deep beams under said deck, and by arranging between this lower deck and the strength deck, at least one longitudinal bulkhead extending over the entire length of the main hold portion of the ship.

This longitudinal bulkhead or bulkheads constitutes a 30 main strength member of the ship and preferably extend through a plurality of adjacent compartments arranged in succession in the longitudinal direction of the ship and also straight through the engine room between the transverse bulkheads enclosing this room. This arrangement 35 is of considerable importance when cargo-holds are provided ahead of as well as aft of the engine room.

By means of the invention the transverse section of the hull is subdivided into at least three cargo spaces of 40 which the lowermost, referred to herein as the "cargo hold" and situated between the tank top and the lower deck nearest to the tank top, will be entirely free from vertical supports, centre-line bulkheads and brackets along the sideplating. At least two 'tween-deck cargo spaces 45 are obtained between the strength deck and the lower deck. These cargo spaces also are characterized by the absence of vertical supports etc.

A very advantageous embodiment of the invention is 50 obtained by using two longitudinal bulkheads arranged at a suitable distance from each other to provide room for hatches for the cargo-spaces located outwardly of the longitudinal bulkheads and also for the hatches for the lowermost cargo-hold.

It is of particular importance that the 'tween decks 55 cargo-spaces between the side plating and the longitudinal bulkheads can be provided with separate cargo-hatches instead of trunk ports in the longitudinal bulkheads, which would reduce the over-all strength of the hull, in consequence of which the cargo-spaces within the transverse section may be made accessible through three hatches, which can be loaded and unloaded independently 60 of each other.

Two embodiments of my invention will be further described with reference to the accompanying drawings in 65 which:

FIG. 1 is a longitudinal section taken along line I—I of FIG. 2 showing a preferred embodiment of this inven-

tion the bow and stern structures being shown in elevation, and the superstructure in broken lines;

FIG. 2 is a plan view of FIG. 1;

FIG. 3 is a horizontal section taken along III—III of FIG. 1;

FIG. 4 is a schematic view taken substantially along line IV of FIG. 1, and

FIG. 5 is a view similar to FIG. 4 but showing a modification.

As shown in FIGS. 1 and 2, the ship comprises a bow structure 15, and a stern structure 16, which are connected by a main hold portion 17. The midships superstructure 18 is shown in broken lines.

With reference now to FIGS. 1, 2, 3 and 4, the hull comprises a suitable reinforced double bottom comprising bottom plating 1 and a tank top 2, together with side frames and side plating, referred to generally as the side walls 3 and 4. The hull also includes as strength members a plurality of transverse bulkheads 5 and a strength deck 6.

Disposed below the strength deck 6 is a lower deck 7 which extends from one side wall 3 to the other side wall 4, and from one transverse bulkhead 5 to the other. One or more middle decks 8 may be provided between the top deck 6 and the lower deck 7.

The lower deck 7 as well as the middle deck 8, are supported at intermediate points by longitudinal bulkheads 9 and 10 which extend the full length of the cargo space from the bow to the stern as shown in FIGS. 1, 2 and 3. The structural cooperation between the longitudinal bulkheads 9 and 10 and the decks 6, 7 and 8, to which the bulkheads are secured, longitudinally strengthens each compartment without in any way interfering with the cargo space provided in the hold. When the longitudinal bulkheads 9 and 10 extend through several compartments a very substantial longitudinal reinforcement of the entire hull is provided.

The various hatches L, later described, are provided with suitable coamings 11.

The transverse bulkheads 5 thus provide a plurality of separate compartments which are subdivided to provide the different cargo spaces illustrated in FIG. 4 except that one of these compartments may serve as the engine room 12, through the upper portion of which the longitudinal bulkheads 9 and 10 extend as shown in FIGS. 1, 2 and 3.

Thus, as diagrammatically shown in FIG. 4 three separate cargo spaces are provided, a first 'tween-decks cargo space ABGHA, a second 'tween-decks cargo space CDEFC, and a third cargo space BGHIKEFCB. The latter includes the hold proper HGFEKIH, and an auxiliary 'tween-decks space BCFGB, the nature of which is better illustrated in FIG. 1, as constituting the space available between the decks 7, 8 and 6.

Suitable cargo hatches L4 and L5 provide access to 'tween-decks cargo space ABGHA, and similarly, separate cargo hatches L6 and L7 provide access to the 'tween-decks cargo space CDEFC. Cargo hatches L1, L2 and L3 provide access both to the cargo hold proper HGFEKIH and to the auxiliary 'tween-decks space BCFGB. Thus, access may be had to the two main 'tween-decks cargo spaces through hatches L4 and L6 independently of the access to the hold and auxiliary 'tween-decks cargo space. This permits use of the main 'tween-decks cargo spaces for refrigerated loads and other loads, while the heavier loads may be located in the hold proper.

As a consequence of this construction the cargo-space ABGHA with its cargo-hatches L4 and L5 is entirely independent of the cargo-space BCFEIKIHGB, which is accessible through cargo-hatches L1, L2 and L3. Similarly the cargo-space CDEFC is entirely independent of the spaces mentioned, being accessible for loading and unloading through cargo-hatches L6 and L7.

A further consequence of the arrangement is that the different cargo-spaces, and this is particularly noticeable with regard to the largest space, the lowermost cargo-hold

HEKIH, is entirely free from vertical supporting pillars, which, as far as loading and unloading is concerned, is an important and much desired advantage and, moreover, this result is attained without the necessity of using deep beams in the deck 7 and deep side frames, to which said beams are secured.

As a third consequence of the arrangement of decks and bulkheads according to the invention and due to the fact that the lowermost cargo-hold is entirely free from vertical supports, cargo handling equipment may be used without being hindered by any kind of supports. It is therefore easier to work with conveyors and with trucks on the tank top than is the case on ships of conventional construction due to the fact that the movements of the trucks are not hindered in any respect by vertical supports or centre-line bulkheads.

As a fourth consequence the longitudinal bulkheads contribute considerably to the strength of the ship in longitudinal direction, considered as a beam. If the longitudinal bulkheads are not only arranged through the cargo-spaces but also through an engine room located amidships or near amidships with cargo-spaces forward as well as aft, they will, as a fifth consequence, contribute still more to strengthening the hull, considered as a beam.

As a sixth consequence the buoyancy of the ship is increased in case of a leak, due to the fact that the hull will contain a higher number of cargo-spaces which are hermetically separated from each other.

As a seventh consequence of the construction the proportions of a fire in any one of the spaces will be more limited than with constructions of conventional design.

As an eighth consequence it may be emphasized that the load can be brought into place with smaller movement in the longitudinal as well as in the transverse direction of the ship due to the fact that the load-hatches can easily be arranged so as to cover greater parts of the deck surface below the hatches compared with the conventional arrangement with hatches only on the centre-line of the ship.

As a ninth consequence it may be mentioned that the vertical longitudinal bulkheads will act as feeders if the ship is loaded with corn.

In part, the above-mentioned advantages are also attained in the modified arrangement shown in FIG. 5 in which the corresponding elements are designated by the same reference numerals, primed. However, instead of having two longitudinal bulkheads 8 and 9, only a single longitudinal bulkhead 13 is provided along the centre-line of the ship. Here the 'tween-decks cargo spaces OPSRO, and PQTSP are provided in addition to the cargo hold RSTVUR. Access to the 'tween-decks cargo spaces is provided by hatches L8 and L10, whereas these same hatches together with hatches L9 and L11 also provide access to the main cargo hold. Thus the 'tween-decks cargo spaces in the FIG. 5 embodiment of my invention are more nearly analogous to the auxiliary 'tween-decks cargo space BCFGB of FIG. 4, since access is not attained through separate hatches such as L4 and L6 of FIG. 1.

What I claim is:

1. In a dry cargo ship having a bow structure, a stern structure, and a main hold portion extending between said bow and stern structures, and which includes as strength members, a double bottom, side walls, a strength deck, and a plurality of transverse bulkheads, said transverse bulkheads dividing said main hold portion into a plurality of compartments, the combination of additional longitudinal hull reinforcing means which includes longitudinal bulkhead means extending continuously from said bow structure to said stern structure and intersecting and being secured to said transverse bulkheads, said longitudinal bulkhead means constituting a main strength member, a lower deck supported in part by said side walls and transverse bulkheads and in part by said longitudinal bulkhead means, said longitudinal bulkhead means being secured to said strength deck and extending only between said lower

deck and said strength deck, whereby those portions of said compartments which are located beneath said lower deck and between said transverse bulkheads provide a plurality of cargo holds which are free from vertical deck supporting means, and a plurality of sets of hatches in said strength deck and said lower deck and located one above the other to provide access to at least some of said cargo holds, said lower deck providing a 'tween decks cargo space located adjacent to the lower deck hatch of each set, the strength deck hatch of each set also providing access to said 'tween decks cargo spaces, said longitudinal bulkhead means being free from trunk ports formed therein and forming at least one wall of said 'tween decks cargo spaces.

2. A dry cargo ship as claimed in claim 1 in which said longitudinal bulkhead means comprises two longitudinal bulkheads arranged on either side of the center line of said ship, said sets of hatches comprising hatches centrally located between said bulkheads.

3. A dry cargo ship as claimed in claim 2 in which said two longitudinal bulkheads and said lower deck cooperate with each other to provide two 'tween decks cargo spaces disposed outwardly of each of said first mentioned 'tween decks cargo spaces and which are entirely separated from each other and from said cargo hold, and in which said sets of hatches further comprise separate cargo hatches formed in said strength deck outwardly of said longitudinal bulkheads to provide access to said outwardly disposed 'tween decks cargo spaces, said first mentioned 'tween decks cargo space providing an auxiliary cargo space which extends fore and aft of said centrally located sets of hatches, said outwardly disposed and said auxiliary 'tween decks cargo spaces being constructed and arranged to receive lighter loads so that the heavier loads can be received in said cargo holds and supported directly on said double bottom.

4. A dry cargo ship as claimed in claim 1 in which said longitudinal bulkhead means comprises a single longitudinal bulkhead disposed along the center line of said ship, there being two of said sets of hatches for each of said cargo spaces, one on either side of said single longitudinal bulkhead.

5. A dry cargo ship as claimed in claim 1 having an engine room located in one of said compartments, said longitudinal bulkhead means extending through said engine room.

6. A dry cargo ship as claimed in claim 1 in which said lower deck extends longitudinally through a plurality of adjacent compartments and extends continuously across said compartments from one side wall to the other, and cooperates with said longitudinal bulkhead means as a strength member.
